J. T. JANETTE

CENTRIFUGAL SWITCH

Filed March 30, 1925

UNITED STATES PATENT OFFICE.

JOHN T. JANETTE, OF CHICAGO, ILLINOIS.

CENTRIFUGAL SWITCH.

Application filed March 30, 1925. Serial No. 19,403.

This invention relates to centrifugal or automatic switches adapted for use in connection with electric motors and more particularly with such motors of the split phase 5 alternating current type. The invention relates to the general construction of such switches, but it is particularly directed to the mounting of the weights and the arrangement of the contact disk and supporting parts.

The objects of this invention are to provide an improved centrifugal switch which is adapted to be actuated when the rotor or part upon which it is mounted reaches a 15 predetermined speed; to provide pivoted arm supports for the weights which will have little or no tendency toward binding and which are provided with interlocking portions to limit the opening and closing 20 movements; to provide a reversible contact disk with means for supporting the same and means for causing the supporting means to rotate with the rotor shaft; to provide a spring tension for holding the weights in 25 normal position and means whereby the tension will be decreased as the weights swing outwardly; to provide an auxiliary spring for holding the contact disk against the stationary contact brushes; and to provide 30 such other novel features and advantages as will be described hereinafter.

In the accompanying drawings illustrating this invention,

Figure 1 is a side view showing a rotor or 35 armature with my improved switch applied thereto;

Figure 2 is a sectional view taken on the line 2—2 of Figure 1;

Figure 3 is a sectional view taken on the 40 line 3—3 of Figure 2; and

Figure 4 is a view similar to Figure 1, showing the switch opened, that is with the weights in extended position and the contact disk drawn away from the stationary 45 contacts.

The switch is shown applied to a rotor 5 of any suitable construction, which is mounted on a shaft 6. The disk or movable switch member 7 is rotatably mounted 60 on a sleeve or collar 8, which is adapted to slide freely on the shaft 6, and is insulated therefrom. The insulating disks or supports 9 are held on the sleeve 8 by means of spring rings 10 and 11. The contact disk

or switch member 7 is normally held against 55 the fixed brushes or contacts 12 and 13 by a spring 14 which engages with one end of the sleeve 8 and abuts at the other end against the rotor 5.

A plate 15 is secured to the rotor and has 60 pairs of ears or bearings 16 and 17 which are diametrically opposed to each other. Pins 18 and 19 are carried respectively by the ears 16 and 17, and form pivots for the oppositely disposed pairs of weight 65 supporting arms or levers 20 and 21. The arms 20 are secured to or formed integrally with a plate or segment 22 to which is secured the weight 23. The arms 21, which are duplicates of the arms 20 are also connected with a plate 24 to which is secured the second weight 25. The arms 20 and 21 are provided on the opposite sides with co-acting lugs or stops 26 and 27 which limit 70 the inward or closing movement thereof, as shown particularly in Figure 1. The extended or opening movement of the weights may be limited by the plates or segments 22 and 24 coming into engagement with the pivoted ends of the arms 20 and 21. The plates or segments 22 and 24 are provided 75 respectively with pairs of ears or lugs 28 and 29 which extend laterally or toward the arm pivots. These opposed lugs are connected by tension springs 30 on opposite sides of the shaft, which tend to draw the segments and connected parts toward the shaft or center. It will be noted on account 80 of positioning the springs rearwardly or adjacent to the pivots, the weights will have a differential action on the springs so that as the weights move outwardly and the springs move toward the pivots, the force necessary to overcome the tension of the 85 springs will be gradually decreased, due to the toggle or leverage action.

I have found it desirable to cause the 90 sleeve 8 to be rotated with the shaft so that when the disk 7 is in engagement with the stationary disks, any rotative movement 95 which may occur will be between the disk and its supporting parts. This is accomplished by means of projections 31 on the sleeve, which are provided with slots 32 for receiving fingers 33, which extend rearwardly from the segments 22 and 24 and are substantially parallel to the shaft 6. These 100 fingers are provided with shoulders 34

- which engage with the outer faces of the projections 31 for forcing the sleeve backwardly or toward the rotor when the weights swing out.
- 5 The stops 26 and 27 are arranged so that the contact disk 7 is permitted to engage with the fixed contacts, under the action of the spring 14, shortly before the weights reach their innermost position. As long as 10 the weights are in such position, the disk will remain in engagement with the contacts, but as soon as the speed of the motor reaches a predetermined point, the weights will swing outwardly and toward the rotor.
- 15 This will cause the shoulders 34 to press against the projections 31 and move the sleeve backwardly, so that the disk is withdrawn from the stationary contacts and the switch is opened. On account of pivoting 20 the levers on opposite sides of the shaft so that they extend across the shaft to support a weight on the opposite side, the length of the levers is increased, which tend to prevent binding and improves the opening 25 movement of the switch. It will also be noted that when the contact disk 7 becomes worn on one side, it may be readily reversed so that the opposite side may be used for making contact.
- 30 My improved switch may be made in various sizes and the parts may be modified in order to adapt it to different types of motors or other devices in which a centrifugal switch may be utilized and therefore I 35 do not wish to be limited to the exact construction herein shown and described except as pointed out in the following claims, in which I claim:
1. A centrifugal switch construction comprising a rotatable shaft, a sleeve loosely mounted on said shaft, a reversible contact disk carried by said sleeve and insulated therefrom, means for holding said sleeve and disk in normal engaging position, and 40 rotatable means adapted to be actuated by centrifugal force for moving the sleeve and disk out of engaging position.
2. In a device as per claim 1, the combination with a sleeve, of a reversible contact disk, means for insulating the disk from the sleeve, and spring rings for holding the disk on the sleeve.
3. In a switch construction, the combination with a rotor and its shaft, of a sleeve 45 slidably mounted on the shaft, a contact disk carried by the sleeve, means for insulating the disk from the sleeve, a spring tending to hold the sleeve with the disk in normal engaging position, arms pivotally secured 50 to the rotor and projecting across to the opposite sides of the shaft, weights carried by said arms, means for connecting the arms with the sleeve, whereby the sleeve will be moved out of engaging position when 55 the arms swing outwardly, and yielding means tending to draw the arms together or in switch closing position.
4. In a centrifugal switch construction, the combination of a rotatable member, a shaft carrying said member, a sleeve on said shaft, a contact carried by the sleeve and adapted to engage with fixed contacts adjacent to the shaft, pairs of arms pivotally secured to the rotatable member on opposite sides of the shaft and extending across the shaft, the arms on opposite sides of the shaft crossing each other and provided with interlocking stops, weights secured to the free ends of the pairs of arms, springs connected with the ends of the arms and tending to draw them toward the shaft, and means for connecting the arms with the sleeve to cause the sleeve to move longitudinally of the shaft when the arms are swung on their pivots.
5. In a switch construction, the combination with a rotor and its shaft, of a sleeve mounted for longitudinal movement on the shaft, a spring interposed between the sleeve and the rotor, means for causing the sleeve to rotate with the shaft, a contact disk rotatably mounted on the sleeve and free from said spring, which spring tends to hold the disk in engaging position, and centrifugally operated means for moving the sleeve longitudinally of the shaft.
6. In a switch construction, the combination with a rotatable member and its supporting shaft, of a sleeve mounted on said shaft, a contact disk rotatably mounted on the sleeve and adapted to make contact with fixed contacts adjacent to the shaft when the sleeve is in normal position, a pair of arms pivotally secured to the rotatable member and extending across the shaft, a plate connecting the free ends of the arms, a weight secured to said plate, a second pair of arms pivotally secured to the rotatable member on the side opposite from the pivot of the first named arms, said second named arms projecting beyond the shaft, a plate connecting the free ends of said last named arms, a weight secured to said plate, fingers projecting from the plates toward the pivots, springs connecting said fingers for drawing the ends of the arms inwardly, projections extending outwardly from said sleeve and having slots in the ends thereof, shouldered tongues on the plates for engagement with said projections to cause the sleeve to rotate with the shaft and also to move the sleeve longitudinally of the shaft, and stops on the arms for limiting the swinging movement thereof.
7. A device as per claim 6, having crossed pivoted weight supporting arms and springs associated with the arms and adapted to move toward the pivots when the arms swing outwardly, whereby the power necessary to be exerted by the arms for opening

the same against the tension of the springs will be decreased as the free ends of the arms swing outwardly.

arrangement being such that the pressure on the contacts is independent of the switch opening means.

10. A device as per claim 6 having pairs 5 of integrally formed weight supporting plates and arms which are duplicates of each other, said arms having interlocking projections for limiting the movements thereof.

10. 9. In a centrifugal switch construction, the combination of a rotatable shaft, of a movable contact slidably mounted on the shaft and adapted to engage with fixed contacts, yielding means tending to hold the 15 movable contact in engagement with the fixed contact, and centrifugal means for withdrawing the movable contact from the fixed contacts to open the switch, the ar-

10. 10. A centrifugal starting switch, comprising a slideable contact support, a contact insulated from said support, a spring tending to move said contact support to contacting position, a rotatable member, weights pivotally mounted on said member, springs tending to hold said weights in retracted position, means connecting the weights and the contact carrier whereby the carrier will be moved by the swinging movement of the weights and a stop for limiting the inward movement of the weights whereby the switch will be closed under tension of the first mentioned spring only.

JOHN T. JANETTE.
